VALVE.

Application filed January 22, 1926. Serial No. 82,888.

Our invention relates to valves in general and particularly to valves which are adapted for use in combination with inflatable articles such as footballs, basket balls, soccer balls, volley balls and balls of similar construction which are adapted for different types of athletic contests.

It is our object to provide an inexpensive valve preferably made entirely of resilient material such as rubber which will be easy to inflate, which will be very resistant against leakage and which will be exceedingly simple to deflate.

It is specifically our object to provide a valve of tubular shape having a neck or stem of resilient material and in which a passage extends from the exterior partially through the stem longitudinally. In combination with such a tubular member, it is our object to provide a slit extending laterally through the walls with a resilient member enclosing at least the slotted part of the tube, which resilient member will expand with inflation from position closing the lateral slit and which will thereafter seal the slit when inflation has ceased. It is further our object to provide the tubular member with a sealed inner end which will form a seat for a valve deflating tool so that the stem of the valve may be stretched and the slit be thereby moved to unsealed position with relation to the resilient member enclosing it. The deflation of the valve may be accomplished by the insertion of any narrow implement through the air passage which is of sufficient length to more than reach to the sealed end.

Referring to the drawings illustrating several modifications of valves embodying our invention:—

Figure 1 is a sectional view of a valve in which an outer resilient sealing member is formed from a bent over end of the valve stem with the bent over portion held against the slit in the tube by the natural stiffness of the valve stem and the body of material in the bent over portion being of sufficient bulk to stay normally in sealing position.

Figure 2 is a sectional view of another type of valve in which a bent over sealed end is held in position by a tying member.

Figure 3 is a sectional view of a slightly different type of valve having a resilient band surrounding the tube with the upper

part of the band held in position by vulcanizing to the valve stem.

Figures 4, 5 and 6 are sectional views of a valve of the same type as that illustrated in Figure 3 with the resilient band held in place at its upper end by interlocking grooves and beading in the walls of the stem and band.

We have illustrated in the several embodiments of our invention the valve stem 1, which must have an inner end of stretchable nature such as rubber. The valve stem has an inflating passage 2 of desired shape extending longitudinally from an open end at the outside part-way through the tube, and the walls of the stem have a slit 3 close to the inner sealed end of the tube, which extends laterally through the walls. The inner end of the tube may be sealed either by bending over the end of the stem and vulcanizing or cementing the end of the tube as indicated at 4 in Figures 1 and 2, or by only extending the longitudinal passage partway through the tube leaving the inner end sealed as indicated at 4 in Figures 3 to 6. All the embodiments have a resilient member 5 which lies over the tube in the position perforated by the slit 3. The resilient member 5 in each case is adapted during inflation to expand sufficiently to allow air to enter through the slit. The members 5 are also adapted, due to their resilience and the inward pressure from the inflatable body of the ball, to seal the slit normally against leakage back through the air passage in the stem. In the Figures 1 and 2 the member 5 is formed from an integral piece of the stem which is bent over and either held in position by having sufficient body to stay in position as indicated in Figure 1 or by a tying member 6 as indicated in Figure 2. Figure 3 shows the resilient member 5 formed as a band extending about the stem being held in position by cementing or vulcanizing as indicated at 7. Figures 4 to 6 are similar in principle to the embodiment shown in Figure 3, excepting the co-operating grooves 8 and beads 9 retain the upper portion of the resilient band in position on the stem.

We have shown as convenient means of securing the stem in position extending through a hole in the inflatable member

which is usually termed the bladder the flanges 10 which may be vulcanized or cemented to a bladder 10^a either on the outer or inner side in the obvious manner. The 5 modifications illustrated in Figures 1, 3 and 6 have outer flanges 11, which may be suitably secured to a cover flap 11^a on the outer side of the bladder.

In inflating a ball provided with a valve 10 made in accordance with our invention, an inflating nozzle is inserted into the outer mouth of the passage 2, and the air passes down through the passage and out through the slit 3 into the inflatable member in which 15 the valve is secured. The pressure within the bladder in combination with the resiliency of the member 5 effectively seals the slit against leakage back through the air passage in the stem. 20 In deflating the bladder an elongated tool such as a piece of square wire is inserted in the air passage from the open end and pressed against the sealed end of the stem which stretches the stem so that the slit is 25 moved to an unsealed position with reference to resilient member 5. In the modifications shown in Figures 1 and 2, as the resilient members 5 are carried by the end of the stem, the resilient members themselves are moved 30 to unsealing position, with the stretching of the stem. In the modifications shown in Figures 3 to 6, the stem is stretched so that the slitted portion is carried below the resilient band. It is preferable in the modifications

shown in Figures 3-6, to have the upper part 35 of the band secured permanently in position on the stem so that it will not move down with the stretching of the stem so as to continue to block the slitted portion of the stem. 40

Modifications of structure which provide valves which have a stretchable stem with a longitudinal passage closed at the inner end and with a lateral slit which is adapted to be sealed against back leakage by a resilient 45 member disposed exteriorly of the stem, we consider within the range of mechanical equivalency.

Having thus described our invention, what we claim as new and desire to secure by Letters Patent, is:—

A valve for inflatable articles comprising a stem portion having an open ended air passage extending longitudinally thereto, said stem having a closed inner end, walls of 55 said stem having a slit extending laterally therethrough adjacent said closed end, and a resilient member supported by said stem enclosing the outer walls of said stem in the slitted portion, said stem being stretchable whereby pressure applied with an inserted piece within said air passage bearing against said closed end will stretch said stem and unseal said slit with relation to said enclosing member.
